ABSTRACT

A golf club head with a cavity at least partially filled with a non-Newtonian shear thinning filler material is disclosed herein. The filler material may comprise multiple materials, such as microbubbles or microbeads, composite polyol materials, blowing agents, and/or graphene to improve performance and dampen sound after the golf club head impacts a golf ball.

No. 9,808,685, which claims priority to U.S. Provisional Patent Application No. 62/457,086, filed on Feb. 9, 2017, each of which is hereby incorporated by reference in its entirety.

STATEMENT REGARDING FEDERALLY SPONSORED RESEARCH OR DEVELOPMENT

Not Applicable

BACKGROUND OF THE INVENTION

Field of the Invention

The present invention relates to an iron-type golf club head with one or more shear-thinning materials filling at least a portion of a cavity within the iron-type golf club head.

Description of the Related Art

There is a need for golf club heads, and particularly irons, with one or more filler materials having improved sound damping properties.

BRIEF SUMMARY OF THE INVENTION

One aspect of the present invention is a golf club head with a filler comprising at least one shear thinning material, which reduces viscosity when force is applied. When a golf ball impacts the face of this golf club head, the shear thinning filler material reduces viscosity and allows the face to flex. As the force dissipates, the material's viscosity increases, which increases the damping properties of the material.

Another aspect of the present invention is a golf club head comprising a body comprising a striking face, a sole portion, a top portion, a rear portion, and a cavity, and a non-

Newtonian shear thinning filler material, wherein the cavity is at least partially filled with the filler material. In some embodiments, the filler material may comprise polypropylene carbonate and thermoplastic polyurethane. In other embodiments, the filler material may comprise a plurality of microspheres. In still other embodiments, the filler material may comprise a plurality of microbubbles, which may be composed of a polymer material or glass. In another embodiment, the filler material may comprise a plurality of Expanceel expandable microspheres. In still other embodiments, the filler material may comprise at least one material selected from the group consisting of silicone polyol, polyester polyol, polyether polyol, and polycarbonate polyol. In any of the embodiments, the filler material may further comprise graphene. In another embodiment, the filler material may comprise urethane with air pockets created by the reaction of isocyanate with water to create CO₂. In another embodiment, the filler material may be memory foam.

Having briefly described the present invention, the above and further objects, features and advantages thereof will be recognized by those skilled in the pertinent art from the following detailed description of the invention when taken in conjunction with the accompanying drawings.

BRIEF DESCRIPTION OF THE SEVERAL VIEWS OF THE DRAWINGS

FIG. 1 is a cross-sectional view of a first embodiment of the golf club head of the present invention with the inventive non-Newtonian shear thinning filler material.

FIG. 2 is a chart illustrating the relationship between viscosity and stress for Newtonian and non-Newtonian materials.

DETAILED DESCRIPTION OF THE INVENTION

The present invention is directed to a golf club head, and particularly an iron or hybrid-type golf club head with one or more cavities that are at least partially filled with one or more shear thinning, non-Newtonian fill materials. A preferred embodiment of a golf club iron 10 of the present invention is shown in FIG. 1. The iron 10 includes a face component 20 with a striking surface 22 that is affixed to a body section 30 with a sole portion 31, a top portion 32, and a rear portion 33 to form an interior cavity 15, which is filled with a non-Newtonian, shear thinning filler material 50. In the preferred embodiment, the non-Newtonian filler material 50 is a urethane comprising Expanceel expandable microspheres, which are described in greater detail at nouryon.com/products/expanceel-microspheres. Preferably, the Expanceel is added to the urethane mixture and when the mixture cures, voids are created due to the expansion of the microsphere in reaction to heating. The viscosity of the material 50 changes based on force placed on the material 50, and the voids created by the Expanceel within the material 50 allow it to compress under those forces.

In another embodiment, the non-Newtonian filler material 50 is composed a polymer material that is softer than urethane and that comprises glass microbubbles. In other embodiments, the non-Newtonian filler material 50 includes one or more blowing agents. In still other embodiments, the non-Newtonian filler material 50 is created from urethane to which water is added during mixtures to create bubbles by polyurea formation. Isocyanate from urethane reacts with water to create CO₂, which creates air pockets in the resulting filler material 50.

In any of the embodiments disclosed herein, graphene powder, such as C-650, can be added to the non-Newtonian filler material 50 to improve its overall durability. In another embodiment, the filler material 50 comprises two parts silicone based on addition cure. In another embodiment, the filler material 50 comprises one part silicone based on condensation cure. In another embodiment, the filler material 50 comprises one part silicone based on peroxide cure. In any of the embodiments, the filler material 50 is a hybrid polyurethane comprising silicone polyol, polyester polyol, polyether polyol, and polycarbonate polyol.

In other embodiments, the golf club head 10 may have a multi-material composition such as any of those disclosed in U.S. Pat. Nos. 6,244,976, 6,332,847, 6,386,990, 6,406,378, 6,440,008, 6,471,604, 6,491,592, 6,527,650, 6,565,452, 6,575,845, 6,478,692, 6,582,323, 6,508,978, 6,592,466, 6,602,149, 6,607,452, 6,612,398, 6,663,504, 6,669,578, 6,739,982, 6,758,763, 6,860,824, 6,994,637, 7,025,692, 7,070,517, 7,112,148, 7,118,493, 7,121,957, 7,125,344, 7,128,661, 7,163,470, 7,226,366, 7,252,600, 7,258,631, 7,314,418, 7,320,646, 7,387,577, 7,396,296, 7,402,112, 7,407,448, 7,413,520, 7,431,667, 7,438,647, 7,455,598, 7,476,161, 7,491,134, 7,497,787, 7,549,935, 7,578,751, 7,717,807, 7,749,096, and 7,749,097, the disclosure of each of which is hereby incorporated in its entirety herein.

From the foregoing it is believed that those skilled in the pertinent art will recognize the meritorious advancement of this invention and will readily understand that while the present invention has been described in association with a preferred embodiment thereof, and other embodiments illustrated in the accompanying drawings, numerous changes, modifications and substitutions of equivalents may be made therein without departing from the spirit and scope of this invention which is intended to be unlimited by the foregoing except as may appear in the following appended claims. The section titles included herein also are not intended to be limiting. Therefore, the embodiments of the invention in which an exclusive property or privilege is claimed are defined in the following appended claims.

We claim:

1. A golf club head comprising:
a body comprising a striking face, a sole portion, a top portion, a rear portion, and a cavity; and
a non-Newtonian shear thinning filler material,
wherein the cavity is at least partially filled with the filler material;

wherein the filler material comprises urethane with air

pockets created by the reaction of isocyanate with

water to create CO₂.

2. A golf club head comprising:
a body comprising a striking face, a sole portion, a top portion, a rear portion, and a cavity; and
a non-Newtonian shear thinning filler material,
wherein the cavity is at least partially filled with the filler material;

wherein the filler material is memory foam.
